(57) **CLAIM**

The ornamental design for an umbrella runner grip, as shown and described.

DESCRIPTION

FIG. 1 is a bottom perspective view of an umbrella runner grip showing my new design.

FIG. 2 is a front or rear view of the design of FIG. 1;

FIG. 3 is a right or left side view of the design of FIG. 1;

FIG. 4 is a top view of the design of FIG. 1;

FIG. 5 is a bottom view of the design of FIG. 1;

FIG. 6 is a front view of the new umbrella runner grip, showing the grip in a first position; and,

FIG. 7 is a rear view of the new umbrella runner grip of FIG. 1, showing the grip in an optional second position.

Phantom lining and/or broken lines, where utilized, are for illustration purposes only and form no part of the claimed design.

1 Claim, 6 Drawing Sheets
